UNITED STATES PATENT OFFICE

156,394

WINDOW SHELF

Loren Yohey, Muncie, Ind., assignor to Rodgers-Yohey Body Corporation, Muncie, Ind., a corporation of Indiana

Application April 13, 1948, Serial No. 145,694

Term of patent 7 years

(Cl. D33—3)

To all whom it may concern:

Be it known that I, Loren Yohey, a citizen of the United States and resident of Muncie, in the county of Delaware and State of Indiana, have invented a new, original, and ornamental Design for a Window Shelf, of which the following is a specification, reference being had to the accompanying drawing, forming a part thereof.

Figure 1 is a plan view; Figure 2 is a front view; Figure 3 is an end view; and Figure 4 is a perspective view of a window shelf showing my new design.

I claim:

The ornamental design for a window shelf, as shown.

LOREN YOHEY.
